UNITED STATES PATENT OFFICE.

JOHN BERG, OF CHICAGO, ILLINOIS, ASSIGNOR TO METAL SPECIALTIES MANUFACTURING COMPANY, OF CHICAGO, ILLINOIS, A CORPORATION OF ILLINOIS.

ELECTRIC CONNECTOR.

1,085,960.

Specification of Letters Patent.

Patented Feb. 3, 1914.

Application filed November 8, 1912. Serial No. 730,158.

To all whom it may concern:

Be it known that I, JOHN BERG, a citizen of the United States, residing at 736 West Monroe street, Chicago, in the county of 5 Cook and State of Illinois, have invented new and useful Improvements in Electric Connectors, of which the following is a specification.

My invention relates particularly to electric connectors, such as are used for connecting electric conductors together, or for connecting electric conductors to any electric device, such as an electric lamp, or other electric device.

15 The primary object of the invention is to provide an electric connector of improved and simplified construction.

The invention is illustrated in the preferred embodiment in the accompanying drawing, in which—

Figure 1 represents an elevational view of a connector embodying my invention, shown connected with an electric lamp; Fig. 2, a broken elevational view showing the connector used for joining two electric conductors; Fig. 3, an enlarged sectional view of the socket-portion of the connecting device shown in Figs. 1 and 2, the section being taken as indicated at line 3 of Fig. 4; Fig. 4, an end view of the socket shown in Fig. 3; Fig. 5, a perspective view of a double-terminal member employed in the socket shown in Fig. 3; Fig. 6, a section taken as indicated at line 6 of Fig. 3; Fig. 35 7, a broken elevational view of one of the plugs shown in Figs. 1 and 2, showing the parts separated; Fig. 8, a front end view of the plug shown in Fig. 7; Fig. 9, a sectional view showing a socket of modified construction; Fig. 10, an elevational view showing a modified form of the connector-plug; Fig. 11, an elevational view showing my improved connector, in slightly modified form in conjunction with a socket of the 45 form shown in Fig. 9, and Fig. 12, a view like Fig. 10, showing a further modification.

Referring to Figs. 1 to 8 inclusive, A represents a double-end socket; B, a plug connected with one end thereof; and C, an electric lamp connected with the other end of said socket. It should be explained, however, that in Fig. 2 the lamp C has been replaced by another plug B.

50 In the preferred construction of the socket A, I employ a tubular metal member 1,

within which is located an insulating plug 2 encircled by an insulating sleeve 3. The plug 2 is provided on opposite sides with longitudinal segmental grooves 4 which accommodate a pair of double-terminal members 5. Each member 5 has a longitudinal body-portion 6 received by the groove 4 and has inwardly bent terminals 7. Each member 5 is made of springy material. The terminals 7 are suitably spaced with relation to the ends of the plug 2, so that they are capable of yielding. The body-portion 6 of each member 5 is shouldered at its extremities, as indicated at 8, the shoulders 8 being adapted to engage the 70 end surfaces of the plug 2 at the ends of the slots 4. The sleeve 3 serves to insulate the members 5 with respect to the tubular member 1. It serves, also, to secure the members 5 in the channels 4, said members 75 being thus firmly held in place without the use of screws or attaching devices.

The member 1 has its ends projecting beyond the ends of the plug 2 and provided with bayonet slots 9. The construction described affords two sockets 10 and 10^a, which may be of unequal length, as shown.

The members 5 may comprise stampings, and are capable of being cheaply produced. It will be understood that each stamping 85 is so formed that the grain of the metal is continuous, so that there will be no danger of breaking the terminals. Each terminal 7 is preferably curved edgewise, as shown in Fig. 4, and the extremities or contact points 90 7^a of the terminals are preferably disposed diametrically opposite each other.

The plug or connector B preferably comprises an insulating plug 11 having terminals 12 extending therethrough; and a conductor-housing 13 detachably connected with the plug 11. Conductors 14 are connected with the rear ends of the terminals 12. These conductors may be secured to the terminals 12 by screws 15 in the usual manner.

The plug 11 is equipped with laterally projecting studs 16. The conductor-housing 13 comprises an elongated cap having its bottom or rear end-portion provided with a 105 central perforation 17 through which the conductors 14, which may be contained in a single sheath 18, extend. The member 13 may be drawn or stamped from sheet metal. In forming the perforation 17, it is pre- 110

ferred to curve the marginal portion 19 of the metal inwardly, so as to provide a rounded surface and avoid danger of chafing the cord 18. The cylindrical portion of the member 13 is provided near the advance or open end of the member with bayonet-slots 20 which are adapted to engage the lateral studs 16 of the plug. The member 13 is also provided with a circumferential bead 21, which may be knurled, as shown in Fig. 1, to facilitate manipulation of the cap. The studs 16 are of sufficient length to protrude through the bayonet-slots 20 and to enter the bayonet-slots 9 of the socket shell 1. Thus, the studs 16 serve to secure the member 13 to the plug 11, and also serve to secure the plug B in the socket 10, for instance.

When desired, the member 13 may be turned to disengage the bayonet-slots 20 from the studs 16, after which the member 13 may be withdrawn to the position shown in Fig. 7, giving access to the plug to enable the connections to be examined and repaired if necessary.

It is understood, of course, that when the plug B is inserted in the socket A and turned to the locking position, the terminals 12 will engage the contact points 7^a of the socket terminals 7. The lamp C is of a form now in common use, having a stem or plug-portion 22 which enters the socket, and is provided with lateral studs 23 which enter the bayonet-slots 9. The stem or socket-portion 22 of the lamp is equipped, of course, with the usual terminals which terminate at the inner end of the stem and are adapted to engage the terminals 7 of the socket.

As shown in Fig. 2, the plug B may be substituted for the lamp C. In other words, the plug and lamp are interchangeably fitted to the socket-member A.

In the construction shown in Figs. 9 and 11, A' represents a single-end socket comprising a shell 23 and a plug 24. It will be noted that the plug 24 corresponds with the plug 11, while the addition of the shell 23 affords a socket 23^a. In this form the plug 24 is fitted with longitudinal posts or conductors 25, to which are applied suitably bent flat spring terminals 26. The conductors 27 connect with the rear ends of the posts 25. The plug 24 is fitted with a laterally projecting stud or pin 28 adapted to be engaged by the bayonet-slot 20 of a conductor-housing or cap 13^a. The member 13^a is similar to the member 13 already described, except that the bayonet-joint 29 differs somewhat from the bayonet-joint 20. The bayonet-joint 29 has an oblique or inclined portion 29^a adapted to act like a thread or screw to force the forward edge of the shell or cap 13^a against the rear edge of the shell 23. The cap may be of springy material and adapted to fit snugly on the plug 24;

and if desired, the pin and slot connection between the plug and cap may be omitted.

Fig. 10 shows a modified form of connector-plug B'. This is similar to the plug B, except that the shell or cap 13^b is provided with an internal rib or shoulder 30, adapted to bear against the rear end of the plug 11, and the stud 16 works in a bayonet slot 31 having a spiral portion 31^a provided with a slight indent, or locking-recess 31^b. When the member 13^b is turned to the securing position, the stud 16 works in slot 31^a as in a screw-thread, while the shoulder 30 engages the rear edge of the plug 11. The tongue of metal 32, which is resilient, is thus sprung somewhat, and the stud 16 finally passes into locking engagement with the recess 31^b.

Fig. 12 shows a construction like that of Fig. 10 except that for the shoulder 30 is substituted a resilient shoulder 30^a, formed by striking a small tongue of metal inwardly from the shell 13^c.

The improved construction is simple, durable and thoroughly effective, and may be produced at very low cost. The advantages of the improved construction will be appreciated when it is understood that there is an annual demand in this country for many millions of such devices.

The foregoing detailed description has been given for clearness of understanding only, and no undue limitation should be understood therefrom, but the appended claims should be construed as broadly as permissible, in view of the prior art.

What I regard as new and desire to secure by Letters Patent is:

1. In an electric connector, a socket comprising a shell, an insulating plug therein provided at its periphery with longitudinal channels, a pair of terminal members having body-portions confined in said channels, each terminal member having shoulders engaging the ends of the plug and having laterally bent extremities disposed near the end surfaces of said plug, and an insulating sleeve confined between said plug and shell and embracing the body-portions of said terminals.

2. In an electric connector, the combination with a socket comprising a tubular member provided with a bayonet-slot and a plug in said tubular member equipped with an electric terminal, of a conductor-equipped plug comprising an insulating plug equipped with a terminal and equipped also with a lateral stud, a conductor connected with said last-named terminal and extending from one end of said last-named plug, and a conductor-housing comprising a cap having an opening through which the conductor extends and having its advance edge-portion extending into said tubular member and provided with a bayonet-slot, the bayonet-

slots of said tubular member and cap engaging said stud.

3. In an electric connector, a socket comprising a tubular member, an insulating plug therein provided at its periphery with a longitudinal channel, a terminal member extending through said channel and having a laterally bent yielding end-portion spaced with relation to the adjacent end of said plug, and means insulating said terminal from said tubular member and holding said terminal without other connection in said channel.

4. In an electric connector, a socket comprising a shell, an insulating plug therein provided with longitudinal channels, substantially flat resilient terminal members extending through said channels and having their end-portions bent across the end surface of the plug, and spaced with relation thereto to afford contact points, and insulating means within the shell and serving alone to confine said terminal members in said channel.

5. In an electric connector, a socket comprising a shell, an insulating plug therein provided at its periphery with longitudinal channels, terminals having body-portions extending into said channels, and an insulating sleeve snugly embracing the body-portions of said terminals, said sleeve fitted snugly in said shell and serving to secure said terminals in said channels.

6. In an electric connector, a socket comprising a shell, separable insulating members therein provided with longitudinal channels, and a pair of terminal members having body-portions confined in said channels wholly by said insulating members, each terminal member having laterally bent extremities disposed near the end surfaces of said insulating members.

7. In an electric connector, the combination with an insulating plug fitted with an electric terminal and provided with a lat-

eral stud, of a conductor connected with said terminal and extending from one end of said plug, and a conductor-housing fitted on said plug and comprising a cap having its rear end provided with an opening through which said conductor extends, said cap having a shoulder bearing against a shoulder on said plug and said cap having its advance edge provided with a bayonet-slot having an inclined portion engaging said stud.

8. In an electric connector, the combination with an insulating plug fitted with electric terminals and provided with a lateral stud, of conductors connected with said terminals and extending from one end of said plug, and a conductor-housing fitted on said plug and comprising a cap having its rear end provided with an opening through which said conductors extend, said cap having its intermediate portion provided with an inwardly-struck shoulder which bears against the rear edge of said plug and said cap having its advance edge provided with a bayonet-slot engaging said stud, for the purpose set forth.

9. In an electric connector, the combination with an insulating plug fitted with electric terminals and provided with a lateral stud, of conductors connected with said terminals and extending from one end of said plug, and a conductor-housing fitted on said plug and comprising a cap having its rear end provided with an opening through which said conductors extend, said cap having its intermediate portion provided with an inwardly-struck resilient shoulder which bears against the rear edge of said plug and said cap having its advance edge provided with a bayonet-slot engaging said stud, for the purpose set forth.

JOHN BERG.
